DESIGN FOR A DISPLAY CASE

Henry K. Tourneau, New York, N. Y.

Application December 8, 1944, Serial No. 116,797

Term of patent 14 years

(Cl. D80—5)

To all whom it may concern:

Be it known that I, Henry K. Tourneau, a citizen of the United States, residing in the city of New York, county of New York, and State of New York, have invented a new, original, and ornamental Design for Display Case, of which the following is a specification, reference being had to the accompanying drawing, forming a part thereof, in which:

Fig. 1 is a top plan view of my new design; Fig. 2 is a side elevational view thereof; and Fig. 3 is a front view thereof.

I claim:

The ornamental design for a display case, as shown.

HENRY K. TOURNEAU.
